APPARATUS FOR APPLYING TERMINALS BY CRIMPING AND SEVERING LEAD TERMINAL FROM CONNECTING STRIP WITHOUT SEVERING SAID STRIP

Quentin Berg, New Cumberland, Pa.

Application May 7, 1956, Serial No. 582,993

3 Claims. (Cl. 153—1)

This invention relates to apparatus for applying terminals and has particular reference to a novel and efficient machine for applying partially preformed wrap around type of terminals in strip form to a conductor and severing such terminals from the strip. The invention is particularly concerned with the application of terminal elements of this type in which such elements are disposed in parallel and each integrally connected at one end thereof in close-coupled arrangement to a connecting strip, and where the final shape of the terminal element is such that the conductor to which it is secured is disposed in overlapping relation with the connecting strip, which connects a series of terminal elements in strip form, during the application of the lead terminal to the conductor. The invention is also concerned with a novel and simple mechanism for severing the lead terminal from its connecting strip when it is applied to a conductor.

A principal object of the invention is to provide a novel, efficient and simple machine for applying terminal elements in strip form to conductors and for severing the terminals from a connecting strip when the terminals are applied to a conductor.

A further object of the invention is to provide a new and improved machine for applying strip terminals to conductors and severing the terminals from the strip wherein the conductors to which the terminals are applied are disposed in overlapping relation with the connecting strip to which the terminal elements are secured.

Other and further objects of the invention will be apparent from the following description and claims and may be understood by reference to the accompanying drawings, of which there are three sheets, which by way of illustration show a preferred embodiment of the invention and what I now consider to be the best mode in which I have contemplated applying the principles of my invention. Other embodiments of the invention may be used without departing from the scope of the present invention as set forth in the appended claims.

In the drawings:

Fig. 1 is a fragmentary perspective view of a press type of apparatus embodying the invention;

Fig. 2 is a perspective view of an electrical component including conductors, to the ends of which a wrap-around type of terminal element has been secured;

Fig. 3 is an enlarged perspective view of a strip of terminal elements of the type with which the apparatus herein disclosed and claimed is particularly useful;

Fig. 4 is an enlarged front elevational view of the apparatus as shown in Fig. 1;

Fig. 5 is an enlarged fragmentary sectional view taken along the line 5—5 of Fig. 4 and showing the relationship of the dies, the lead terminal element, and the conductor to which it is to be applied, at the beginning of a cycle;

Fig. 6 is a view similar to Fig. 5 but showing the relationship of the parts after the lead terminal has been

2

applied to the end of the conductor and severed from its connecting strip;

Fig. 7 is a fragmentary sectional view taken along the line 7—7 of Fig. 5;

Fig. 8 is a fragmentary sectional view taken along the line 8—8 of Fig. 6;

Fig. 9 is an enlarged plan view of a partially preformed terminal element as it is supplied to the applicator; and

Fig. 10 is an enlarged perspective view of an applied terminal element.

The apparatus is particularly adapted for affixing terminal elements to electrical components, such as illustrated in Fig. 2, which may consist of an electrical condenser or resistance 10 having conductors 12 and 14 projecting from the ends thereof. As shown in Fig. 2, the free ends of the conductors 12 and 14 have terminals or terminal elements 16 secured thereto. The apparatus as illustrated is adapted to affix elements 16, one at a time, to the end of a conductor such as 12, although it will be appreciated that by duplication of the apparatus illustrated a terminal 16 may be applied to the free ends of each of the conductors 12 and 14 simultaneously. Furthermore, as illustrated, no feed mechanism is shown for feeding the conductors in position to have the terminals applied thereto as such is not a part of the present invention, although in an applicator embodying the invention which has been built and installed, a feed mechanism was provided for automatically feeding the electrical components to the applicator in timed relation with the operation of the applicator.

As shown in Figs. 3 and 9, the terminals 16, with which the apparatus as illustrated is particularly concerned, are partially preformed, disposed in parallel, and each integrally connected at the conductor projecting end 18 by a portion 20 in close-coupled arrangement to a connecting strip 22. The elements 16 in partially preformed condition as shown in Figs. 3 and 4 are channel-shaped and somewhat conical in form, the sides 24 being in the form of upstanding wings which define an open top side to the element.

To aid in securing the end of the conductor 12 in the element 16, the inside of the element is provided with transverse grooves which are formed by a coining operation, the grooves 26 forming shoulders which are forced into the conductor 12 so as to resist axial separation of the conductor 12 from the terminal 16. The terminal 16 and the conductors 12 may be formed of copper, brass, or any other suitable material. The apparatus illustrated is of the press type which includes a stationary die block 30 and a movable die block 32 mounted for movement toward and away from each other, the upper die block 32 in this case being reciprocably mounted for movement toward and away from the lower die block 30 and a series of guides, such as 34, being provided for maintaining the die blocks 30 and 32 in proper relationship. The die blocks 30 and 32 are mounted on a conventional type of power operated reciprocating press.

The apparatus in general comprises a feed indicated generally at 36, a guide indicated generally at 38, a stationary anvil or die indicated generally at 40, a reciprocating crimping die indicated generally at 42, and a cutoff which is provided by a cutting edge 44 formed on the anvil 40 and a cooperable cutting edge 46 formed on part 84 of the guide 38 (Figs. 5 and 6).

The anvil 40 as illustrated is affixed to the stationary die block 30 while the crimping die 42 is mounted upon the upper die block 32 for reciprocation therewith. The anvil 40 and crimping die are shown in their closed position in Figs. 4, 6 and 8, and in their open position in Fig. 5.

As previously indicated, the terminals are fed in strip form to the apparatus, a strip of the terminals being indicated at 50. The feed mechanism for advancing the strip 50 of terminals so as to dispose the lead terminal element in crimping position with respect to the anvil 40 and the die 42 consists of an arm 52 pivoted at 54 and provided with a roller 56 adapted to roll upon the surface of the cam 58 carried by the upper die block 32. The arm 52 is biased in a counterclockwise direction about its pivot by a spring 60 which is disposed around bolt 62 and confined between fixed stop 64 and a head 66 which includes a roller 68 which is adapted to bear against one end of a feed finger 70, the feed finger 70 being pivoted at 72 to the arm 52 and having an end 74 which is engageable with the elements 16 of the strip 50 upon reciprocation of the feed mechanism for advancing the elements 16 of the strip 50 one by one so as to dispose the lead element thereof in operative position with respect to the top surface 76 of the anvil 40. The strip 50 is supplied from a reel (not shown) of terminals in strip form.

A spring 80 connected with the finger 70 and the arm 52 biases the end 74 of the feed finger 70 into position to operatively engage the elements 16 for feeding the same forward. As the press opens, that is, as the upper die block 32 moves away from the lower die block 30, the roller 56 following the cam 58 under the influence of spring 60 will move the feed finger 70 forward sufficiently to position the lead terminal 16 of the strip 50 on the upper surface of the anvil 40 and on the down stroke of the press the feed finger 70 will be retracted so as to engage the next element 16. On the succeeding upstroke of the press, the lead terminal will be fed to a position for operation upon by the anvil 40 and the crimping die 42.

The guide 38 as illustrated comprises parts 82 and 84 which are constructed and assembled so as to define a longitudinal L-shaped feed channel indicated generally at 86, Fig. 5. The portion 88 of the channel is adapted to guide the connecting strip 22, while the enlarged central part of the channel is adapted to accommodate the terminals 16. The guide 38 is pivoted at 90 to a fixed part of the lower die block 30. A spring 92 biases the guide 38 to the position as shown in Fig. 5. The guide 38 is provided with an opening 94 which intersects the channel 86. The upper end of the anvil 40 is disposed in the opening 94 so that the lead terminal 16 may be positioned thereon, as illustrated in Fig. 5, with the connecting strip 22 overhanging the anvil 40. The part 84 is provided with an exposed groove or slot 96 which forms a means for locating the end of the conductor 12 in position for application of the lead terminal thereto with the conductor 12 disposed in overlapping relation with respect to the connecting strip 22 underlying part 84, and with the lead terminal 16 disposed between the anvil 40 and the end of the conductor 12, and with the open side of the lead terminal facing the conductor 12 and the crimping die 42.

A bracket 98 carried by the die block 30 is provided at its upper end with a groove or notch 100 (Fig. 1) which is aligned with the notch 96 when the guide 38 is in its upper position and which forms a part of the means for locating the end of the conductor 12 for the application of the terminal 16 thereto. As previously indicated, suitable automatic mechanism may be provided for automatically feeding the components 10 to the apparatus for application of the terminals 16 to the ends of the conductors thereof. With the guide 38 in its upper position the end of the conductor 12 is positioned in line with and above the open side of the terminal 16, as shown in Figs. 5 and 7. Upon the closing of the press, the crimping die 42 first seats the conductor 12 in the terminal 16 and then secures the terminal 16 around the conductor 12. To this end the die 42 is provided with a tongue or punch 102 which upon the closing of the press engages the end of the conductor 12 and moves it downwardly into the terminal 16 through the open side thereof. Closing of

the press also causes the guide 38 to move downwardly, against the spring 92. As the die 42 moves downwardly, the bifurcations 104 thereof straddle the terminal 16 and the anvil 40 and engage the sides of the terminal and force the same around the conductor 12 so as to secure and crimp the terminal 16 to the conductor 12, the terminal 16 and/or conductor 12 in the process being deformed by cold flow of the metal as shown in Fig. 8.

As die 42 moves downwardly, the end 106 of a bifurcation 104, or a part movable therewith, engages a part of the guide 38 and moves the same downwardly, thereby causing the cutting edges 46 and 44 to shear the connecting portion 20 of the terminal strip, for severing the lead terminal 16 from the connecting strip 22. The crimping die 42 is formed so that it will cooperate with the anvil 40 to crimp the terminal 16 onto the conductor 12. Upon the upstroke of the press, the die 42 is separated from the lead terminal 16 which is now separated from the connecting strip 22, and the lead terminal may then be removed from the anvil 40, and as previously indicated, the feed mechanism on the upstroke will move the next succeeding lead terminal 16 into position on the anvil 40 for the next operation. The connecting strip 22, devoid of terminals, is discharged from the end of the die 38.

The apparatus may be provided with a stripper 120 (Fig. 4) positioned adjacent the crimping die 42 for stripping the terminal 16 from the crimping die 42 after assembly of such terminal to the conductor if the terminal tends to stick in the crimping die upon the retractile stroke thereof.

By wrap-around type of terminals, I have reference to terminals in which one or more integral portions thereof are bent around or positioned so as to grip an insulated or uninsulated conductor so as to connect the terminal to the conductor, the specific terminal illustrated being by way of example. This may include, as here, cold flowing the terminal so as to exceed the elastic limit of the terminal material. The extent to which such terminals are preformed before being supplied to the applicator may vary, and I contemplate that the preforming operations may, if desired, be performed in the press illustrated by providing the same with suitable dies ahead of the crimping dies 40 and 42.

The connecting strip 22 after being discharged from the guide 38 may be fed to a cutter indicated generally at 122 for cutting the strip 22 into small pieces. The cutter consists of a cutting edge 124 carried by and movable with the upper die block 32 and a cutter 126 mounted on the lower die block 30.

While I have illustrated and described a preferred embodiment of my invention, it is understood that this is capable of modification, and I therefore do not wish to be limited to the precise details set forth but desire to avail myself of such changes and alterations as fall within the purview of the following claims.

I claim:

1. Apparatus for applying wrap-around type of terminal elements having an open side to conductors wherein the terminal elements are disposed in parallel and each integrally connected at one end thereof in close-coupled arrangement to one side of a connecting strip, said apparatus comprising a stationary anvil, means for feeding a strip of such terminal elements in a path leading to said anvil so that such connecting strip is disposed laterally of and passes to one side of said anvil and the lead terminal element is positioned on said anvil and projects laterally therefrom in overlapping relation with respect to said anvil, with the anvil backing up such lead terminal and with the open side of said terminal facing away from said anvil, guide means engageable with a conductor, which extends across said path and connecting strip, so as to leave the end of such conductor free and projecting in the same direction as said lead terminal and in aligned

overlapping relation with respect thereto, said guide means locating such free end of the conductor in position for application of said lead terminal thereto with the conductor disposed in overlapping transverse relation with respect to said connecting strip and with the lead terminal disposed between said anvil and said conductor and with the open side of said lead terminal facing and aligned with the free end of said conductor, a crimping die disposed opposite said anvil and cooperable therewith by movement toward the same for crimping said terminal on the free end of said conductor, said crimping die and anvil being offset laterally of and out of alignment with the path of movement of said connecting strip, said die being engageable with the sides of said terminal element for crimping the same around the end of said conductor, and a cutoff operable by movement of said crimping die for severing said lead terminal from said connecting strip without severing said connecting strip, said crimping die engaging and holding said lead terminal on said anvil from a time prior to severing of such terminal from 20 said strip until completion of the crimping operation.

2. Apparatus according to claim 1 wherein said crimping die includes a tongue engageable with the free end of said conductor for moving the same therewith toward said anvil, and into said terminal element through the 25

open side thereof and for seating and holding such free end in said terminal during the crimping operation.

3. Apparatus according to claim 1 wherein said cutoff comprises cooperable cutting edges on said stationary anvil and said guide means disposed laterally of and out of alignment with the path of movement of said connecting strip, said cutting edge on said guide means being movable when the lead terminal is applied to said conductor for cooperation with the cutting edge on said anvil for severing the lead terminal from said connecting strip, said guide means being interposed between said connecting strip and said conductor.
